CONTAINER WITH ROTATABLE SPOUT

Frank J. O'Brien and Henry A. Fink, Pelham Manor, N. Y., assignors to Continental Can Company, Inc., New York, N. Y., a corporation of New York

Application November 5, 1936, Serial No. 109,376

1 Claim. (Cl. 221—11)

The present invention relates to new and useful improvements in dispensing containers, and more particularly to a metal container having a combined closure means and pouring spout.

- 5 An object of the invention is to provide a can top having a mouth which is sealed by a closure bung, which closure bung is so constructed that the pouring spout is rotatably attached thereto and forms in effect a unit therewith.
- 10 A further object of the invention is to provide a combined bung and spout wherein the bung has a raised portion scored to provide a pouring opening, and the spout has a member serving to cover the opening when the spout is not in pouring
- 15 position.

These and other objects will in part be obvious and will in part be hereinafter more fully disclosed.

In the accompanying drawing:

20 Figure 1 is a top plan view of the dispensing container showing the pouring spout in closed position.

Figure 2 is a similar view showing the pouring spout in a dispensing position.

25 Figure 3 is an enlarged sectional view taken along the line 3—3 of Fig. 1.

Figure 4 is an enlarged sectional view taken along the line 4—4 of Fig. 2.

30 The invention relates generally to a metal container for dispensing oil or other liquid products.

The container ends are secured to the body portion preferably by double-seaming. The top end has a mouth with an upstanding outwardly tapering flange surrounding the same. A cuplike bung fits within said mouth and contacts with

35 said flange for closing the mouth. The bung has a skirt which overlies said flange and contacts with the outer face thereof for attaching the bung to the can top, the metal forming a part of said skirt being crimped around said upstanding flange for effecting a tight seal therewith.

40 The bung has a raised central portion which is expanded at its upper portion to provide an overhanging ledge. The container is provided with a tapered pouring spout having a projecting

45 pouring lip and a portion fitting beneath the ledge on the bung for securing the spout in rotatable relation therewith. The raised portion of the bung has a section thereof scored for removal to

50 provide a pouring opening, and the spout has an integral projecting member which is adapted to cover said opening when turned to a position within the limits of the can top and uncovering said opening when said spout is in pouring position.

Referring more in detail to the drawing, the container consists of a body portion 5 having a top end 6 double-seamed thereto as indicated at 7. The top end 5 is provided with a mouth 8 and an upstanding outwardly tapering flange 5 9 which surrounds said mouth. A cuplike bung 10 fits within said mouth and contacts with said flange 9. The bung 10 has a skirt 11 which overlies and is crimped around the flange 9 for effecting a tight seal between the bung and the top end.

The bung has a central raised portion 12 spaced from the skirt 11 which is expanded to provide an overhanging ledge 13. The upper face of the bung indicated at 14 in the drawing 15 has a score line 15 which may be readily ruptured to provide a pouring opening for the container.

The container is provided with a pouring spout 16 having a pouring lip 17 and a depending portion 18 which is adapted to fit beneath the ledge 13 for securing the spout to the bung while permitting said spout to rotate about the same. The spout is also provided with an integral member 19 which is adapted to cover the pouring opening in the raised face of the bung when the 25 spout is turned to a position as shown in Fig. 1 of the drawing, and uncovering said opening when the spout is in pouring position, as clearly shown in Fig. 2 of the drawing.

From the above it will be apparent that a dispensing means has been provided for a container which is very simple in construction and which includes a pouring spout permanently but rotatably attached to the closure bung. The spout may be turned so as to house the same within 30 the limits of the top, and when so positioned, the pouring opening formed by the rupturing of the metal is covered and closed. When the spout is turned to the position so as to overhang the double seam, then the opening is uncovered and 35 the contents may be freely poured from the container into the spout and discharged by the spout away from the side wall of the container.

It will be obvious that minor changes in the details of construction and arrangement of the 45 parts may be made without departing from the spirit of the invention as set forth in the appended claim.

We claim:

A can comprising a body and a can top having 50 a mouth with an upstanding outwardly tapering flange and a cuplike bung adapted to fit within said mouth and contact with said flange, said bung having a skirt overlying said flange and contacting with the outer face thereof for sealing 55

the bung to the can top, said bung having a raised central portion expanded at its upper portion to provide an overhanging ledge, a spout having a projecting pouring lip and a portion fitting beneath said ledge for securing the spout to the bung while permitting said spout to rotate in said bung, said raised portion having a section thereof scored for removal to provide a pouring open-

ing, and said spout having means for covering said opening when turned to a position within the limits of the can top and uncovering said opening when said spout is in pouring position.
